UNITED STATES PATENT OFFICE.

GAMMEL ANDERSEN, OF AUSTIN, TEXAS.

CLIP.

Application filed April 17, 1922. Serial No. 554,165.

To all whom it may concern:

Be it known that I, GAMMEL ANDERSEN, citizen of the United States, residing at Austin, in the county of Travis and State of Texas, have invented certain new and useful Improvements in a Clip, of which the following is a specification.

This invention relates to new and useful improvements in a clip.

10 One object of the invention is to provide a clip of the character described adapted to be carried by a fountain pen, or pencil, and provided for the purpose of securing the article to which it is attached to the fabric 15 of the pocket wherein said article is carried.

Another object of the invention is to provide a clip of the character described, which may be easily released from said fabric, when it is desired to remove the pen or pencil 20 from the pocket of the garment in which it is carried.

With the above and other objects in view the invention has particular relation to certain novel features of construction and 25 use, an example of which is given in this specification and illustrated in the accompanying drawings, wherein:—

Figure 1 shows a side view of the clip in engaging position.

30 Figure 2 shows a side view thereof in released position and,

Figure 3 shows a plan view thereof.

In the drawings the numeral 1 designates the cap of a fountain pen to which the clip 35 is secured. This clip is formed of one piece of spring material such as spring brass, silver, or other suitable material. One end of the clip is secured in the usual and customary way to the cap 1. A section 2 of 40 the clip extends out at substantially right angles to the article to which it is attached and then is bent into substantially parallel relation with said article, said parallel section being indicated by the numeral 3. The 45 free end of the piece of material is then bent under said parallel portion and for a distance lies closely adjacent thereto, and it is then turned outwardly forming a shoulder 4, and beyond the shoulder it extends straight, in inclined relation to the section 3, and the extreme free end is curved 50 outwardly forming an engaging catch 5 adapted to engage with the material 6 of

the pocket of the garment. A clip is shown in engaging position in Figure 2, with the 55 catch 5 biting into the fabric. When it is desired to remove the pen the free end 7 of the clip is depressed, as shown in Figure 2 and the shoulder 4 will operate as a fulcrum and the catch 5 will be disengaged 60 from the fabric and the pen may then be easily removed.

What I claim is:—

1. A clip formed of a single piece of 65 spring material one end of which is formed for attachment to a pen or pencil, a section of said material being bent at right angles to the attached end and the free end of said piece of material being bent back under said bent over section and being 70 formed with a shoulder and an engaging catch beyond said shoulder, which points toward said pen or pencil.

2. A clip for pens and the like, said clip 75 being formed of a single piece of spring metal one end of which is formed to be attached to the pen and extending at approximately right angles thereto, a section of the piece of metal being bent over into substantially parallel relation with said pen and the free end thereof being turned under and formed with a shoulder which projects toward the pen and forms a fulcrum and said free end beyond said shoulder being 80 formed into an engaging catch which points toward said pen.

3. A clip for pens and the like formed of 85 a single piece of metal bent at substantially a right angle, one end of said piece being formed for attachment to a pen or similar 90 article, and the other end of said piece being doubled back on itself the doubled back portion being formed with a shoulder forming a fulcrum, and its free end being outwardly turned forming a catch.

4. A clip for pens and the like formed of a single piece of metal bent at substantially a right angle, one end of the clip being adapted to be secured to the pen and a section of the other end lying substantially 100 parallel with said pen, the free end of said parallel section being bent under and for a portion of the way lying closely adjacent the parallel section and being then bent outwardly from said parallel section forming a shoulder which provides a fulcrum, 105

the free end beyond said shoulder lying approximately parallel with said parallel section and terminating in an overturned catch which points toward said pen, said fulcrum 5 operating to move said catch outwardly from the pen when the free portion of said clip is forced inwardly toward the pen.

In testimony whereof I have signed my name to this specification in the presence of two subscribing witnesses.

GAMMEL ANDERSEN.
